(57) **CLAIM**

I claim the ornamental design for a substrate thermometry unit, as shown (and described).

DESCRIPTION

FIG. 1 is a front, top and left side perspective view of a substrate thermometry unit showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a cross sectional view take along line 6-6 in FIG. 2 thereof;

FIG. 9 is a cross sectional view take along line 7-7 in FIG. 2 thereof;

FIG. 10 is an enlarged portion view taken along line 10-10 in FIG. 4 thereof

FIG. 11 is a cross sectional view take along line 11-11 in FIG. 10 thereof;

FIG. 12 is an enlarged portion view taken along line 12-12 in FIG. 6 thereof; and,

FIG. 13 is a cross sectional view take along line 13-13 in FIG. 12.
